UNITED STATES PATENT OFFICE.

EDWARD BEACH GALLAHER, OF PHILADELPHIA, PENNSYLVANIA.

DESIGN FOR A VEHICLE-BODY.

SPECIFICATION forming part of Design No. 34,548, dated May 21, 1901.

Application filed April 13, 1901. Serial No. 55,798. Term of patent 7 years.

To all whom it may concern:

Be it known that I, EDWARD BEACH GALLAHER, a citizen of the United States, and a resident of Philadelphia, in the county of Philadelphia and State of Pennsylvania, have invented and produced a new and useful original Design for a Vehicle-Body, of which the following is a specification, reference being had to the accompanying drawings, forming part thereof.

Figure 1 is a side view of the vehicle-body. Fig. 2 is a rear view of the same. Fig. 3 is a transverse vertical section taken in the plane of the line 3 3 of Fig. 1, and Fig. 4 is a transverse vertical section taken in the plane of the line 4 4 of Fig. 1.

As shown in the accompanying drawings, the leading or material feature of my design is the configuration of the profile of the vehicle-body when viewed in side elevation, as shown in Fig. 1, and the configuration of the arms and back of the seat shown in the several figures. When viewed in side elevation, the profile has its bottom straight, and the lower part of its back is flat, as shown at *a*, and curved inwardly, as shown at *b*, from the flat lower part *a* to the seat and has its front

below the seat curved inwardly, as shown at *c*, from the seat to the upper edges of the sides of the foot-board *d*. The sides have 30 panels *e*, the edges of which conform to the straight bottom, straight seat, and inwardly-curved portions *b* and *c*. Along the sides and back of the seat is a beaded molding *f*, and along the curved front *c* is a beaded molding 35 *g*, which also extends along the upper edges of the foot-board *d*. The arms and back of the seat consist of a continuous solid railing *h*, which is curved around the rear corners of the seat, the back of which railing is 40 surrounded by a back-rest *i* of corresponding curvature. An inwardly-curved dashboard *j* uprises from the front end of the foot-board *d*.

What I claim is—

The design for a vehicle-body, substantially 45 as herein shown and described.

In testimony that I claim the foregoing as my invention I have signed my name, in presence of two witnesses, this 8th day of April, 1901.

EDWARD BEACH GALLAHER.
